JOHN M. KOHLEFING, OF ST. LOUIS, MISSOURI, ASSIGNOR, BY MESNE ASSIGNMENTS, TO
CHICAGO RAILWAY EQUIPMENT COMPANY, A CORPORATION OF ILLINOIS.

BRAKE-BEAM STRUT.

1,140,616.

Specification of Letters Patent. Patented May 25, 1915.

Original applications filed June 24, 1911, Serial Nos. 635,218 and 635,219. Divided and this application filed September 12, 1912. Serial No. 720,027.

To all whom it may concern:

Be it known that I, JOHN M. KOHLEFING, residing at 915 Olive street, St. Louis, Missouri, and being a citizen of the United States, have invented certain new and useful Improvements in Brake-Beam Struts, of which the following is a full, clear, and exact description, such as will enable others skilled in the art to which it appertains to make and to use the same, and is a divisional application of Serial Nos. 635,218 and 635,219, filed June 24, 1911, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1, is a fragmentary plan view of a portion of a brake beam showing a preferred embodiment of my invention in position thereon. Fig. 2 is an enlarged detail view of the strut employed between the intermediate portion of the stress members, the latter shown in section; Fig. 3 is a transverse sectional view of the same taken on a plane indicated by the line 3—3 of Fig. 2, and looking in the direction indicated by the arrow. Fig. 4 is a view similar to Fig. 2, but showing a modified form of strut and connection, and Fig. 5 is a view similar to Fig. 3, but taken on the line 5—5 of Fig. 4.

My invention relates in general to a strut for trusses, and particularly relates to such a member disposed between the stress element of the brake beam in car construction.

It is desirable in car construction to unify and simplify the structural parts so as to reduce the number of repair parts necessary to have on hand, and it has heretofore been necessary to carry two kinds of brake beam struts, one for the right and one for the left hand brake lever for inside and outside hung brakes.

It is an object of this invention to construct a brake beam strut so formed that castings from the same pattern may be used in the construction of brake beams adapted for use either upon the front or rear sides of a car truck.

A still further object of my invention is to provide in a device of the above outlined

character, means for frictionally and positively holding the strut in position relative to the stress members.

I attain the above outlined objects by providing a strut the ends of which are substantially alike, and provided with seats for the compression and tension members of the brake beam, whereby the strut is reversible, end for end, so as to bring the usual diagonally disposed bearing pocket of the brake lever into position inclined in either direction from the vertical.

My invention also includes means co-acting with either end of the strut, for securing the same frictionally to the compression or channel member, and also includes means for positively connecting either end of the strut to the compression member.

Referring to the drawings by numerals: 1, indicates the compression member and 2 the tension member of the beam. The compression member may be straight throughout its length, but is preferably slightly bowed, and comprises a channel section arranged with its web standing vertical, and its flanges turned inwardly, that is toward the tension member. The tension member comprises an element with its opposite ends disposed adjacent the opposite ends of the compression member and with its central portion spaced away from the compression member.

In order that the strut between the stress members may be reversible and interchangeable, it comprises a casting 3, formed with its ends identical, and each comprising a yoke 4. The yoke 4, at one end straddles the tension member 2, in the illustration shown to be a round rod, or different in cross sectional area from that of the compression member, and is thereby held from displacement on said tension member, due to the holding of the same in the pocket formed between the bifurcated yoke within the lines of the pocket for the compression member. The legs of the yoke at the opposite end fit snugly between the flanges of the compression member, the end faces and the inclined faces of the yoke affording a seat for the compression member.

As the compression member is preferably of commercially rolled channel iron, and as shown has the inner walls of its flanges converging toward the web of the channel, there is thereby afforded

a wedging action between the outer beveled faces of the yoke, and the inner faces of the flanges of the channel, this construction affording an arrangement by which a blow of a hammer on the strut will firmly wedge one end of the same between the flanges of the channel member. To more positively prevent movement of the strut 3, longitudinally of the compression member a pair of rivets 5 are extended through alined apertures 6—6 in the flanges of said compression member and in the end portion of the strut. A U-bolt 7 is extended through the apertures 6 at the opposite end of the strut bridging the yoke 4 outside of the tension member 2, so that the same apertures 6 are used at opposite ends either to accommodate rivets to hold the same to the compression member, or to accommodate the holding bolt 7. The intermediate portion of the strut 3 is formed with the usual diagonally disposed bearing pocket or slot 8, for the brake lever, not illustrated; the slot 8 preferably does not extend throughout the length of the body portion of the strut, but terminates some distance short of the ends thereof, so as to provide the solid head portion 3^a integral with the body portion. Each head portion may be reinforced by means of the longitudinally and outwardly extending ribs 3^b forming, as shown in dotted lines Figs. 3 and 5, a cruciform braced wall, which adds materially to the strength of the strut as a column. In the modification shown in Figs. 4 and 5 there is substituted for the rivets 5, a strap 5' which is fitted about the outside of the compression member and has its opposite ends bent toward each other as at 6, and engaging behind shoulders 7—7' formed upon upper and lower sides of the strut 3. The strap 5' is riveted to the web of the compression member as at 5'' and the hollow of the yoke 4, at this end of the strut, is adapted to receive the head of said rivet or rivets. The opposite ends of the strap 5' are fixed rigidly to the end of the strut by binding members 9—9 fitted over the outer surfaces of the ends of said strap and bent to fit against opposite sides of the strut, as at 10—10, being secured by bolts 11—11, extending through the bent portions of said members 9, and through the strut. The extreme ends of each of the members 9 are bent outwardly as at 12—12 and serve to lock the nuts of the bolts 11—11. The device herein disclosed has the usual single pin hole 13 although applicant may of course make use of two pin holes if desired, and it will be understood that the strut may be reversed so that any wear which might have occurred in the pin opening, as shown in the dotted lines *a* in Fig. 2, will be taken up by the changed position of the strut, and the unworn wall *b* of the pin

opening will now be located in front of the pin to receive the strain and wear.

With this construction, it will be apparent that castings from the same pattern may be used with either of its ends fixed to the compression member thus disposing the diagonal pocket 8 to right or left according as one or the other end is fixed to said member.

The invention contemplates a strut having seats for tension and compression members of different cross sectional areas at each end which enables it to be reversed for right or left hand brake levers either in the repair of beam, or in changing beams from right to left, or in the assembling of the parts forming the beam as originally made.

What I claim is:

1. A one piece reversible strut for brake beams having seats for tension and compression members of different sectional areas at each end, said strut also having an angulated brake lever slot whereby it may be reversed and used for right or left hand beam.

2. A strut having seats for the compression and tension members at the same end.

3. A strut having seats for the compression and tension members at both ends.

4. A brake beam comprising a compression member and a tension member, a strut between said members, a strap embracing one of said members and having one of its ends extended over said strut, and a binding member engaging said end and being fixed to opposite sides of said strut.

5. A brake beam comprising a compression member and a tension member, a strut between said members, a strap embracing one of said members and having one of its ends extended over said strut, a binding member engaging said end and being bent upon opposite sides of said strut, and means extending through said strut for fixing said binding member to said strut.

6. A strut having two seats at each end, one being within the lines of the other.

7. A reversible strut having seats at each end for interchangeably receiving either the compression or tension member.

8. A brake beam comprising compression and tension members of different sectional areas, and a strut between said members, said strut being formed with a plurality of seats at each end so as to be reversible to accommodate the compression or tension member at either end.

9. A brake beam comprising compression and tension members of different sectional areas, and a strut between said members, said strut being formed with a plurality of seats at its opposite ends so as to be reversible and when reversed to properly cooperate with said members.

10. A brake beam comprising a channel

compression member and a tension member in the form of a rod; a strut between said members, said strut being formed identical at each end so as to be reversible and to co-operate with the channel compression member and tension rod in either position.

11. A brake beam comprising a channel compression member and a tension rod, a strut between said members, said strut having an angulated lever slot and being formed identical at each end whereby said strut may be reversed to change the angularity of said lever slot.

12. A strut having seats for tension and compression members at each end, the seat for the tension member being located within the seat for the compression member, and the seat for the compression member providing tapering surfaces for co-operating with the legs of the compression member.

13. A reversible strut having seats for the compression and tension members at each end and fastening means connecting said strut with one of said members.

14. A reversible strut having seats for the compression and tension members at each end and locking means connecting said strut with one of said members.

15. A reversible strut having seats for

the compression and tension members at each end and a strap connected to one end of said strut and adapted to straddle the compression member.

16. A reversible strut having seats for the compression and tension members at each end and a strap connected to one end of said strut adapted to straddle the compression member and means maintaining said strap in engagement with said compression member.

17. A reversible strut having seats at each end for interchangeably receiving either the compression or tension member and means for fixedly securing the strut upon the compression member.

18. A strut having a seat at each end adapted to receive a tension member, and being formed at each end with inclined walls affording means for wedging the strut in engagement with the flanges of the compression member.

In witness whereof I have hereunto set my hand in the presence of two witnesses.

JOHN M. ROHLFING.
